(57) **CLAIM**

The ornamental design for agricultural gauge wheel arm with split end head, as shown and described.

DESCRIPTION

FIG. 1 is a perspective view of the agricultural gauge wheel arm with a split end head, according to the present invention. FIG. 2 is a right side elevation view of the arm shown in FIG. 1.

FIG. 3 is a left side elevation view of the arm shown in FIG. 1.

FIG. 4 is a right end elevation view of the arm shown in FIG. 1.

FIG. 5 is a left end elevation view of the arm shown in FIG. 1.

FIG. 6 is a top plan view of the arm shown in FIG. 1; and, FIG. 7 is a bottom plan view of the arm shown in FIG. 1. Structure shown in broken lines form no part of the claimed design.
